FILM PROJECTOR TOY

Laurie J. Campbell, Erie, Pa., assignor to
Louis Marx & Co., Inc.

Filed Dec. 14, 1965, Ser. No. 173

Term of patent 14 years

(Cl. D34—15)

FIG. 2

FIG. 3

FIG. 1

FIG. 1 is a front view of a film projector toy embodying my new design;

FIG. 2 is a side elevational view thereof;

FIG. 3 is a top plan view thereof;

FIG. 4 is a rear view thereof;

FIG. 5 is a view similar to FIG. 2 showing the opposite side of the film projector toy;

FIG. 6 is a bottom plan view thereof.

I claim:

The ornamental design for a film projector toy, as shown.
